Primary Examiner — Deanna L Pratt(74) *Attorney, Agent, or Firm* — Mark Miller(57) **CLAIM**

The ornamental design for a display screen of a computing device with graphical user interface, as shown and described.

DESCRIPTION

A portion of the disclosure of this patent document contains material to which a claim for a copyright is made. The copyright owner has no objection to the facsimile reproduction by anyone of the patent document or the patent disclosure, as it appears in the Patent and Trademark Office patent files or records, but reserves all other copyright rights whatsoever. The SINGLE view is a front view of a display screen of a computing device with graphical user interface in some embodiments.

The broken lines showing a display screen is included for the purpose of illustrating an environment of the claimed design. Other broken lines showing certain numbers, words, and/or other elements are also included for purposes that form no part of the claimed design.
